UNITED STATES PATENT OFFICE.

ALFRED H. HUMPHREY, OF NEW YORK, N. Y.

GAS-STOVE.

1,280,740.

Specification of Letters Patent. Patented Oct. 8, 1918.

Application filed May 18, 1916. Serial No. 98,337.

To all whom it may concern:

Be it known that I, ALFRED H. HUMPHREY, a citizen of the United States, residing at New York, county of New York, State of New York, have invented certain new and useful Improvements in Gas-Stoves, of which the following is a specification.

This invention relates to improvements in gas stoves.

10 My improvements are especially designed by me for embodiment in portable gas stoves although certain features are readily adapted and are desirable for embodiment in non-portable stoves.

15 The main objects of this invention are:

First, to provide an improved gas stove which is very efficient in the matter of heat radiation.

Second, to provide an improved gas stove 20 which is very efficient in the matter of combustion of gas.

Third, to provide a gas stove having radiating elements in which the elements are heated and quite uniformly incandescent.

25 Fourth, to provide an improved gas stove well adapted for use in fire places or grates.

Fifth, to provide an improved gas stove which may be made highly ornamental and one in which the ornamentation can be 30 greatly varied without change in structural features.

Further objects, and objects relating to structural details, will definitely appear from the detailed description to follow.

35 I accomplish the objects of my invention by the devices and means described in the following specification. The invention is clearly defined and pointed out in the claims.

40 A structure which is a preferred embodiment of my invention is clearly illustrated in the accompanying drawing, forming a part of this specification, in which:

Figure I is a front view of a structure embodying the features of my invention, a portion of the radiating elements being shown in conventional form, a second pair of interchangeable front legs being shown by dotted lines, and a pair of dogs, which may 50 be substituted for the front legs, being shown in disassembled relation.

Fig. II is a front perspective view of the base with the walls mounted thereon, the style of legs shown in Fig. I by dotted lines being shown in this figure by full lines. 55

Fig. III is a detail vertical section from front to rear on a line corresponding to line 3—3 of Fig. I.

Fig. IV is a detail vertical section on a line corresponding to lines 4—4 of Figs. I 60 and V.

Fig. V is a detail horizontal section on a line corresponding to line 5—5 of Fig. I with the fire back and corner members or upright finishing members omitted. 65

Fig. VI is a detail vertical section from front to rear on a line corresponding to line 6—6 of Fig. I, showing the form and arrangement of the fire back and the relation of the radiating elements thereto. 70

Fig. VII is a detail vertical section on a line corresponding to line 7—7 of Fig. III, showing the mounting for the front legs as shown by full lines in Fig. I.

Fig. VIII is a detail section on line 75 corresponding to line 8—8 of Fig. I.

In the drawing similar reference characters refer to similar parts throughout the several views, and the sectional views are taken looking in the direction of the little 80 arrows at the ends of the section lines.

Referring to the drawing, I provide a base 1 having downwardly projecting flanges at its edges. This base is preferably a casting. The base is provided with 85 corner sockets 2 adapted to receive the shanks 3 of legs 4. The end flanges 5 of the base are perforated at 6 to receive attaching screws 7 for the leg brackets 8 or 9.

The leg brackets 8 are secured to the post-like legs 10 which may be ornamented as desired. The brackets 8 project outwardly and forwardly from the base so that the legs stand at the front and sides of the base, which makes the structure very attractive. 90

The brackets 9 may be substituted for the brackets 8. These brackets 9 are adapted to engage the dogs 11. With the parts thus arranged, if desired, legs such as are shown by dotted lines in Fig. I and by full lines in 100 Fig. II may be used or these legs may be removed and brackets 8 with their post-like

legs 10 substituted, or if desired, the arm-like brackets 9 may be used; the arms being adapted, as stated, to coact with the dogs 11. By this arrangement it is possible to assemble or mount such of the legs upon the base as is preferred or desired.

- I provide a rear wall 12 and end walls 13. These walls are formed of sheet metal and are supported upon the base by means of the 10 corner rods 14 which are threaded into the base, as clearly shown in Fig. III. The rear wall is provided with bead-like rolls 15 at its ends adapted to embrace or receive the rear corner rods 14. The front ends of the end 15 walls 13 are provided with similar beads adapted to receive the front corner rods while their rear ends are provided with beads adapted to embrace the beads at the ends of the rear wall.
- 20 I mount the fire back 16 upon the base within the walls and at the rear of the rear radiating element positioning lugs 17. This fire back is preferably formed of clay or other earthy material and is provided with 25 an overhang 18 at the front, its face having vertical flutes or grooves 19 therein which extend into this overhang. The fire back 16 is provided with a rear flange 20 and with end flanges 20'. The top bar 21 is 30 channeled to embrace the flange 20, the top bar being engaged upon the rear corner rods 14. The curved end bars 22 are also channeled (see Fig. VIII) to embrace flanges 20' at the ends of the fire back. These bars are 35 engaged upon the corner rods and retained thereon by the nuts 23 and 24. These end bars 22 may be ornamented as desired.

The base plate is provided with lugs 25 which coact with the lugs 17 to support the 40 tubular radiating elements 26 above the openings 26' in the base plate. These radiating elements are formed of earthy material and are foraminated or provided with a plurality of openings, preferably both at 45 the front and rear thereof. The radiating elements are of such length that their upper ends are supported below but adjacent to the overhang 18 of the fire back. The lugs are so positioned that the rear sides of the radiating elements are slightly spaced from 50 the face of the fire back. The burner body 27 is mounted below the base so as to support the burner tips 28 below the openings 26'. The burner structure is preferably that 55 of my co-pending application for Letters Patent for gas burner, and, as the details thereof form no part of this invention, they are not further described herein.

The hearth plate 29 is mounted on the 60 front of the base and is notched at 30 to receive the front ends of the end walls (see Fig. V). The hearth plate has a downwardly projecting flange 31 so that the

hearth plate covers the front of the base. This hearth plate may be ornamented as desired and is removable so that parts may be substituted by the dealer in making up a stove to meet the taste of the purchaser. The corner members 32 are mounted on the hearth plate with their upper ends engaged 65 on the ends of the front corner rods 14. It is not found necessary in practice to further secure these corner members. Thus arranged, the hearth plate and corner members and, if desired, the rear end top bars 75 may be conveniently changed to secure the desired design or finish for the consumer. In other words, the stove is complete as a stove with the fire back assembled on the base and heating elements and burners in 80 position. The front legs may also be changed as desired to suit the requirements of the particular purchaser and the ornamental hearth plate and corner members may be changed as desired. This results in 85 great economy to the manufacturer and dealers and consequent economy to the user.

The stove illustrated is especially designed to be set into a fire place although it may be used in any desired relation.

My improved gas stove is very efficient in that it radiates a large amount of heat and is also efficient in combustion. The combination of the radiating elements with the particular fire back having the overhang as 95 described produces very desirable results in securing uniform incandescence of the radiating elements and in general efficiency.

I have illustrated and described my improvements in an embodiment which I find to be very practical. I have not attempted to illustrate or describe the modifications or variations in structural details which I contemplate as being desirable under certain conditions and for certain adaptations as I 105 believe the disclosure made will enable those skilled in the art to which my invention relates to embody or adapt the same as conditions may require.

Having thus described my invention, what 110 I claim as new and desire to secure by Letters Patent, is:

1. In a gas stove, the combination of a base, end and rear walls terminating at their ends in beads adapted to receive corner rods, the beads at the ends of the rear wall and at the rear ends of the end walls being co-engaged, corner rods secured to said base and arranged through said beads to project therefrom, a fire-back arranged on said base, a hearth-plate mounted on said base, rear and end top bars secured to said corner rods to engage said fire-back, and corner members engaged with the front corner rods to cover the front ends of said end walls.
2. In a gas stove, the combination of a

- base having downwardly projecting flanges at its edges provided with leg sockets at the corners, the end flanges being adapted to receive leg brackets so that legs may be mounted to said sockets or on the outer sides of said end flanges interchangeable legs for said base, rear and end walls mounted on said base, a fire-back arranged on said base within said walls, a hearth-plate removably mounted on the front of said base, and corner members removably mounted at the front ends of said end walls.
3. In a gas stove, the combination of a base, corner rods secured to said base, rear and end walls supported by said corner rods, a fire-back arranged on said base, a hearth-plate removably mounted on said base and notched to receive the front ends of said end walls and having a downwardly projecting front flange covering the front of said base, rear and end top bars secured to said corner rods to engage said fire-back, and corner members removably engaged with the front corner rods to embrace the front ends of said end walls.
4. In a gas stove, the combination of a base, corner rods secured to said base, rear and end walls supported by said corner rods, a fire-back arranged on said base, said fire-back having upwardly projecting flanges at its rear side and ends mounted on said base, a hearth-plate mounted on said base to cover the front thereof, channeled rear and end top bars secured to said corner rods to embrace said rear and end flanges respectively of said fire-back, and corner members disposed at the front ends of said end walls.
5. In a gas stove, the combination of a base provided with burner openings and with radiating element positioning lugs grouped about said openings, rear and end walls mounted on said base, a fire-back arranged on said base at the rear of and in engagement with the rear radiating element positioning lugs, radiating elements disposed on said base between said positioning lugs thereof, a hearth-plate mounted on said base and notched to receive the front ends of said end walls and having a downwardly projecting front flange covering the front of said base, and finishing members mounted above said hearth plate at the front ends of said end walls.
6. In a gas stove, the combination of a base, interchangeable legs for said base, rear and end walls mounted on said base, a fire-back mounted on said base within said walls independently of said rear and end walls, a hearth plate removably mounted on the front of said base, and upright finishing members removably mounted on the front ends of said end walls, said hearth plate and finishing members being independently supported and independently removable so that they may be changed to vary or change the design of the stove.
7. In a gas stove, the combination of a base, rear and end walls mounted on said base, a fire-back mounted on said base within said walls independently of said rear and end walls, a hearth plate removably mounted on the front of said base, and upright finishing members removably mounted on the front ends of said end walls, said hearth plate and finishing members being independently supported and independently removable so that they may be changed to vary or change the design of the stove.
8. In a gas stove, the combination of a base provided with burner openings and with radiating element positioning lugs grouped about said openings, walls mounted on said base, a fire-back arranged on said base at the rear of and in engagement with the rear of said radiating element positioning lugs, said fire-back having a vertically fluted face with an overhang at the top, the flutes being extended into the overhang, foraminated tubular radiating elements disposed on said base between said positioning lugs thereof with their upper ends below but adjacent to said overhang of said fire-back, and burners mounted below said openings in said base.
9. In a gas stove, the combination of a base provided with burner openings and with radiating element positioning lugs grouped about said openings, walls mounted on said base, a fire-back of earthy material arranged on said base at the rear of and in engagement with the rear of said radiating element positioning lugs, said fire-back having an overhang at the top of its face, foraminated tubular radiating elements disposed on said base between said positioning lugs thereof with their upper ends below but adjacent to said overhang of said fire-back, and burners mounted below said openings in said base.
10. In a gas stove, the combination of a base provided with burner openings, walls mounted on said base, a fire-back of earthy material arranged on said base, said fire-back having a vertically fluted face with an overhang at the top, the flutes being extended into the overhang, foraminated tubular radiating elements disposed on said base over said openings thereof and with their upper ends below but adjacent to said overhang of said fire-back, and burners mounted below said openings.
11. In a gas stove, the combination of a base provided with burner openings, walls mounted on said base, a fire-back of earthy material arranged within said walls on said base, said fire-back having an overhang at

the top of its face, foraminated tubular radiating elements disposed on said base over said openings thereof and with their upper ends below but adjacent to said overhang of said fire back, and burners mounted below said openings.

In witness whereof, I have hereunto set

my hand and seal in the presence of two witnesses.

ALFRED H. HUMPHREY. [L.S.]
